GOLF BALL

Frank S. Martin, Cranston, R. I., Thaddeus A. Pietraszek, Fall River, Mass., and Peter Dornik, Jr., Evanston, Ill., assignors to United States Rubber Company, New York, N. Y., a corporation of New Jersey

Application December 10, 1953, Serial No. 28,010

Term of patent 14 years

(Cl. D34—5)

Fig. 1 is a top plan view of a golf ball, showing our new design, and

Fig. 2 is a front elevational view thereof,

Fig. 3 is a fragmentary view greatly enlarged of the golf ball cover, and

Fig. 4 is a sectional view greatly enlarged taken through the cover of the ball.

The ball is symmetrical, and a bottom view thereof would appear identical with Fig. 1. So also a right side, left side or rear elevational view of the ball would appear identical with Fig. 2.

We claim:

The ornamental design for a golf ball, as shown and described.
